(57) **CLAIM**

The ornamental design for a battery, as shown and described.

DESCRIPTION

FIG. 1 is a front, top and left side perspective view of a battery showing our new design according to a first embodiment; FIG. 2 is a rear, bottom and left side perspective view thereof; FIG. 3 is a rear, top and right side perspective view thereof; FIG. 4 is a rear elevational view thereof; FIG. 5 is a front elevational view thereof; FIG. 6 is a top plan view thereof; FIG. 7 is a bottom plan view thereof; FIG. 8 is a right side elevational view thereof; and, FIG. 9 is a left side elevational view thereof.

The broken lines in the drawings showing portions of the battery are included for the purpose of illustrating environmental structure and form no part of the claimed design.
